John Saylor Dempster, Knoxville, Tenn., assignor to Dempster Brothers, Inc., Knoxville, Tenn., a corporation of Tennessee

Application July 28, 1952, Serial No. 301,310

5

4 Claims. (Cl. 294—69)

10

This invention relates to improvements in Enclosed Containers, and more particularly to containers suitable for use with transporting and dumping vehicles such as those disclosed in several United States patents granted to George R. Dempster, as represented by No. 2,281,183, February 28, 1942, and No. 2,369,722, granted February 20, 1945.

Containers suitable for use with such transporting and dumping vehicles are often provided with enclosed tops using hood type closures over the containers, either rounded or rectangular, or of other shape, as have been manufactured heretofore for use with such vehicles. It has been the practice to make such enclosed containers with a top portion welded or otherwise rigidly fixed permanently to the bottom portion thereof and having a door in the top, side or end, for access thereto. Such containers often are made of very large capacity, such as 10 or 12 cubic yards. Because of the size thereof relative to the weight, difficulty has been encountered in the shipment of such containers, resulting frequently in extra shipment charges in proportion to the weight thereof, which penalizes the purchaser of the containers, who is compelled to pay the freight therefor. This is especially true when these are shipped by boat, but it is also true when shipped by rail or truck. Nevertheless, no adequate solution to the problem has been found heretofore.

One object of this invention is to overcome the foregoing objections of shipment and to provide for a more compact nesting of the containers, reducing the overall size thereof during transportation and thereby reducing appreciably the cost of shipment where it is based on size.

A further object of the invention is to improve the construction of an enclosed container to enable this to be collapsed in nested relation during shipment and yet which may be reassembled at the point of destination or use with little trouble and loss of time in assembling the container in usable condition, while providing a structure which is sturdy and rigid in use for containing the many types of materials handled therein.

Still another object of the invention is to provide a detachable connection between the top and bottom sections of an enclosed container which permits the top section to be inverted and nested into the bottom section during transportation, thereby reducing the space required for shipment. At the same time, the top and bottom sections may be reassembled in superposed relation and secured rigidly and steadily in a unitary structure.

These objects may be accomplished according to one embodiment of the invention by providing a container with a bottom section adapted to form the body of the container, and a top section provided with an opening, with or without a closure or door therefor, to gain access into the container. The top section, in use, is secured rigidly but detachably upon the bottom section capable of being detached and removed therefrom, whereby the top section may be nested in the bottom section during transportation, thus reducing appreciably the overall cubage of the container. Detachable fasteners are pro-

2

vided within the respective sections, with bracing means along the adjacent edges thereof whereby a sturdy and rigid structure is provided, without weakening, by reason of the separability of the respective sections.

This embodiment of the invention is illustrated in the accompanying drawings in which:

Fig. 1 is a front elevation of the container, with the sections assembled in superposed relation for use;

Fig. 2 is an end elevation thereof;

Fig. 3 is a cross-section therethrough at the front edge on the line 3—3 in Fig. 1;

Fig. 4 is a similar view at the end edge on the line 4—4 in Fig. 2;

Fig. 5 is a view similar to Fig. 1, with the sections detached and nested for transportation;

Fig. 6 is a similar view from the opposite side;

Fig. 7 is an end elevation thereof partly in section;

Fig. 8 is a cross-section through the rear side on the line 8—8 in Fig. 6; and

Fig. 9 is a view similar to Fig. 8, with the parts superposed in their assembled relation.

Referring to Figs. 1 to 4, and 9, the enclosed container is shown as formed of top and bottom sections, generally designated respectively at 1 and 2, which sections normally are in superposed relation during use of the container and will be first described in this relation. The shape and size thereof may be varied as desired. The top section 1 may be rectangular in cross-section, as illustrated, or of other shape, such as curved, pyramid, etc., either with or without doors for access thereto.

In the form shown the top section 1 is provided with an enclosed top generally designated at 3, and with front and rear walls 4 and 5, respectively, and end walls 6. These several walls are rigidly joined together as by welding or otherwise, forming an enclosed structure formed substantially in one integral piece. An access door is shown at 7 in each end wall 6 for gaining admittance to the interior of the container.

The bottom section 2 is formed with closed front and back walls 8 and 9, respectively, and end walls 10, all of which are joined rigidly together as by welding or otherwise to form a substantially integral unit or piece. The bottom of the container is closed by a drop bottom door generally indicated at 11, which is hinged to the bottom section 2 at 12 along the lower edge of the front wall 8. The door 11 is provided also with pins 13 fixed thereto adapted to receive an end connection on a chain or other flexible device connected with the transporting vehicle for lifting the container.

The upper edge of the front wall 8 of the bottom section is turned inward and forms a rim 14 adapted to cooperate with a flange 15 formed on or secured rigidly to the front wall of the top section 1. In the form illustrated, the flange 15 is formed on an angle bar generally designated at 16 welded to the front wall 4 of the top section 1. Bolts 17 extend through the flanges 14 and 15 at intervals along the length of the container for securing these sections detachably together.

Each end of the enclosed container is formed substantially in the same manner described above with respect to the front side, as illustrated in Figs. 3 and 4. Each end wall 10 is shown as having an inturned rim 18 extending along the width of the container upon which is seated a flange 19, shown as formed on an angle bar 20, welded to the end wall 6 of the section 1. These parts are detachably connected together by bolts 21 extending therethrough at spaced intervals along the width of the container.

It will be apparent from Figs. 1 and 2 that the front and end walls of the top section 1 are set inward, out of vertical alignment with the corresponding parts of the bottom section 2, while the rear walls 5 and 9 of the

sections are in vertical alignment with each other. The connection between the latter is illustrated in Fig. 9, which type of connection may be used between any or all of the other sides of the sections that are in vertical alignment with each other.

Referring to Figs. 2 and 9, these show the rear wall 9 of the bottom section 2 as having an angle bar 22, welded thereto, with outturned flange 23. In like manner the rear wall 4 of the top section 1 also has an angle bar 24 welded thereto, with an outturned flange 25 seated upon the flange 23. These parts are secured together detachably by bolts 26 extending therethrough at spaced intervals along the length of the rear walls of the sections.

The parts are assembled for use in the relation shown in Figs. 1 to 4, and 9, with the top section superposed on the bottom section and detachably secured thereto by the bolts 17, 21 and 26. These hold the sections rigidly in proper relation to each other, enabling the container to be used in the usual manner of such enclosed containers for handling various materials, as customarily employed in connection therewith, and to be transported and dumped in the manner previously described.

When the containers are manufactured, however, these may be collapsed into nested relation, as shown in Figs. 5 to 8. This may be accomplished by removing the detachable fasteners 17, 21 and 26, from the engaged portions of the containers, or the rims formed therebetween, as illustrated at 14—15, 18—19, and 23—25. This will permit the top section 1 to be inverted and nested into the bottom section 2, as shown in Figs. 5 to 8, thereby reducing the cubage of the container approximately one half for transportation. The top section 1 being inverted will be supported by the surrounding rims thereon, which are seated upon the upper edges or rims of the bottom section 2, as will be apparent from the drawings. These parts usually are constructed of steel, whereby the top section 1 is sufficiently heavy to be maintained in place by gravity during transportation. If desired, however, the parts may be fastened together by suitable fastenings such as wire clips and the like, engaging the holes in the respective rims thereof, or bands may be used to enclose the nested container sections.

When the containers reach their destinations, the top sections may be easily lifted out of the bottom sections and inverted onto the latter. The parts may be secured rigidly by inserting the fasteners 17, 21 and 26, which will secure these rigidly together. Little time will be required for this assembling of parts at the point of use, and yet a material saving in the cost of transportation will have been effected by reason of the collapsing of the sections, as described.

A bail is shown at 27, connected with the front wall 8 of the bottom section 2, usually being provided to facilitate the handling of the container upon a vehicle of the type described above. While the bail is shown as welded or otherwise rigidly fastened to the bottom section, it may be hinged thereto if desired for collapsing into a recess in the front wall, as described and illustrated in the patent of George R. Dempster, No. 2,464,441, March 15, 1949.

While I have illustrated and described one embodiment of this invention, it is recognized that variations and changes may be made therein without departing from the invention as set forth in the claims.

I claim:

1. An enclosed container comprising top and bottom sections, each having surrounding side walls with enclosed top and bottom portions thereon, respectively, the front and end walls of the bottom section having inturned flanges thereon forming rims along the upper edges of said side walls, a bail connected with the bottom section of the container at the front thereof and extending therefrom for lifting and supporting the container, an angle bar fixed rigidly to the upper edge of the rear side

wall of the bottom section with an outturned flange thereon, angle bars secured rigidly to the lower edges of the side walls of the top section and having outturned flanges seated upon the flanges on the bottom section, detachable fasteners extending through said flanges and detachably connecting the sections together for removal of the top section and permitting inversion thereof into nested relation within the bottom section, said bottom section including a drop bottom door hinged thereto and having means thereon for detachable engagement by a lifting vehicle.

2. An enclosed container comprising top and bottom sections, each having front and back side walls and end walls, the bottom section having a drop bottom door hinged thereto adjacent the lower edge of the front wall, means connected with the front wall of the bottom section for lifting and suspending the container, the bottom section having an inturned flange on the upper edges of the front wall arranged for clearness of access to the lifting means connected with said front wall, and said bottom section having an outturned flange on the upper edge of the back wall, the top section having out-turned flanges on the lower edges of the front and back walls thereof seated on the flanges of the bottom section, and means detachably connecting said flanges together for removal of the top section and inversion thereof into nested relation within the bottom section.

3. An enclosed container comprising top and bottom sections, each having front and back side walls and end walls, the top section having an opening therein through which material may be inserted into the container, the bottom section having a drop bottom material discharge door hinged thereto adjacent the lower edge of the front wall, a bail connected with the front wall of the bottom section and extending upwardly therefrom for lifting and suspending the container, the bottom section having in-turned flanges on the upper edges of the front and end walls and an outturned flange on the upper edge of the back wall, the top section having out-turned flanges on the lower edges of the front, back and end walls thereof seated on the flanges of the bottom section, and means detachably connecting said flanges together for removal of the top section and inversion thereof into nested relation within the bottom section, the back walls of the top and bottom sections being in vertical alignment with each other when the top section is seated on the bottom section and the other walls of said top section being inwardly offset out of vertical alignment with the corresponding walls of the bottom section, whereby the front wall of the top section is offset from the front wall of the bottom section to permit engagement of the bail for lifting the container.

4. An enclosed container comprising top and bottom sections, each having front and back side walls and end walls, the top section having an opening therein through which material may be inserted into the container, the bottom section having a drop-bottom material discharge door hinged thereto adjacent the lower edge of the front wall, a bail connected with the front wall of the bottom section and extending upwardly therefrom for lifting and suspending the container, the bottom section having flanges on the walls at the upper edges thereof, the top section having flanges on the lower edges of the walls thereof seated on the flanges on the walls of the bottom section, the flange on the upper edge of the front wall of the bottom section being turned inwardly, and the flange on the lower edge of the front wall of the top section being turned outwardly whereby the front wall of the top section is laterally offset from the front wall of said bottom section to permit the insertion of lifting means through said bail, and means connecting said flanges together for removal of the top section and inversion thereof into nested relation within the bottom section.
